UNITED STATES PATENT OFFICE

2,125,884

MACHINE FOR LASTING SHOES

Eli Brothers, Lynn, Mass., assignor to United Shoe Machinery Corporation, Paterson, N. J., a corporation of New Jersey

Application October 4, 1937, Serial No. 167,102

12 Claims. (Cl. 12—7)

This invention relates to the manufacture of shoes and is illustrated herein with reference to machines for use in lasting shoes.

An important object of the invention is to provide an improved machine for use in securing shoe uppers in lasted relation to insoles by cement which will be efficient, economical and easy to operate, and which will expedite the operation of cement lasting a shoe upper.

To this end and in accordance with one feature of the invention, there is provided in a machine of the type referred to means for supporting a shoe the upper of which is to be lasted by cement, in combination with a flexible member for working the lasting margin or allowance of the upper into overlasted relation to an insole, and means for actuating said flexible member in a manner to cause it to operate on portions of the upper located at separated portions of the shoe bottom simultaneously and in planes substantially parallel to the planes of the shoe bottom at which said portions of the upper are located.

As herein illustrated, the flexible member preferably comprises a wire which may be endless and is provided with oppositely disposed loops adapted to surround and engage the lasting margin of the upper at the toe and heel portions of the shoe. The actuating means comprises a roll or drum carrying the flexible member and arranged when in an operative position to locate the loops in positions to work the toe and heel portions of the upper simultaneously into overlasted position. When the roll is rotated the loops of the wire member are drawn toward each other to effect the lasting operation.

In accordance with another feature of the invention the shoe supporting means is arranged also to work the upper at the opposite sides of the shoe into overlasted position, this means, as illustrated herein, comprising a pair of wiper members or forms conforming substantially on their work engaging surfaces to the configurations of the opposite sides of the shoe and overlapping the bottom surface of the shoe for a distance at least equal to the lasting margin thereof.

Further objects and features of the invention, including novel mechanisms for operating the shoe supporting members yieldingly, for moving the flexible lasting member into and out of operative position, and for rotating the roll to actuate the flexible lasting member after it has been located in its operative position, will now be described in connection with the accompanying drawings and will thereafter be pointed out in the claims.

In the drawings,

Fig. 1 is a side elevation of the machine embodying the present invention with parts broken away and in section;

Fig. 2 is a similar view of the upper portion of the machine on an enlarged scale after the machine has operated on a shoe; and

Fig. 3 is a rear elevation of the upper portion of the machine after it has operated on a shoe.

The machine comprises a base 6 and an upstanding hollow column 8 having secured to its upper end by screws 10 a horizontal bracket 12. The bracket 12 is provided with two upstanding walls 14, 16 between the upper portions of which is pivoted on a horizontal shaft 18 a pair of L-shaped levers 20 and 22. The lever 22 has a lateral projection 24 at its upper end to which is pivoted, by a pin 26, a shoe supporting and upper lasting member 28. The lever 20 likewise has pivoted on a lateral projection 30 by a pin 32 a similar shoe supporting and upper lasting member 34. As shown in the drawings, the members 28, 34 are arranged to engage the opposite sides of a shoe from about the tip line to the heel breast line and their configuration is such that they conform substantially to the opposite sides of the portions of the shoe which they are adapted to engage. The members 28, 34 are preferably composed of metal and are faced on their shoe engaging surfaces with relatively yieldable material 36 (Fig. 2), such as leather or rubber. The arrangement of these members on the upper ends of the levers 20, 22 is such that they normally assume the position shown in Fig. 1 relatively to the levers, but are capable of sufficient pivotal movement to permit them to adjust themselves readily to the shape of the shoe. As shown in Fig. 2, when the members 28, 34 are moved into operative relation to a shoe their upper portions overlap the lasting margin of the shoe bottom.

The levers 20, 22 are provided respectively with lower arms 38, 40 which cross each other and to which are pivotally connected by pins 42, 44 a pair of links 46, 48. The lower ends of these links are pivotally connected by a pin 50 to a yoke member or clevis 52 adjustably mounted on the upper end of a rod 54 which extends downwardly through an opening in the bracket 12 into a cage or cylinder 56 arranged for heightwise movement inside the column 8. The lower end of the rod 54 is in the form of a disk 58 which has a sliding fit in the bore of the cylinder and thus acts as a piston. Interposed between the end of the piston 58 and a nut 60 threaded into the top of the cylinder is a relatively heavy compression

spring 62. The nut 60 may be adjusted in the cylinder to vary the tension on the spring 62 and it may be held in adjusted position by a lock nut 64 (Fig. 2).

5 A treadle rod 66 is adjustably secured to the lower end of the cylinder 56 and extends through lugs 68, 70 in the column 8 (Fig. 1) to be connected at its lower end by a pin and slot arrangement 72 to a treadle 74 fulcrumed on a shaft 76. 10 The upward limit of the movement of the treadle is determined by a stop 78 on the base 6 and the treadle is normally maintained in its elevated position by a compression spring 80 surrounding the rod 66, this spring bearing at its lower end against the lug 70 and at its upper end against a collar 82 pinned to the treadle rod. 15

10 The lever 20 has pivotally secured to its upper end on an eccentric pin 84 a casting 86 having a laterally extending elongated portion 88. Rotatably mounted in the casting 86 is a sleeve 90 having formed on its inner or right-hand end, as viewed in Fig. 2, a pinion gear 92. Mounted inside the sleeve 90 is the shank portion 94 of a roll or drum 96 which projects inwardly beyond the casting and is arranged when in an operative position to extend transversely of a shoe bottom at about the center of the shank portion of the shoe, as shown in Fig. 3. The roll or drum 96 is of such a diameter that when located as described above, its top side will lie substantially tangent to the plane of the forepart of a shoe bottom operatively positioned in the machine, and its bottom side will be tangent, or substantially so, to the general plane of the heel seat portion of the shoe. The sleeve 90 and shank portion 94 of the roll are rotatably secured in the casting 86 by a collar 98 bearing against an outer surface of the casting and secured to the sleeve and shank 94 by a pin 100. The roll 96 may be adjusted laterally of the machine for operating on shoes of different widths by the eccentric pin 84.

15 About midway of its length the roll 96 is provided with a diametrical hole 102 as shown in Fig. 3. These opposite ends of the hole 102, as best shown in Figs. 2 and 3, are rounded outwardly to blend smoothly with the surface of the roll. Passing loosely through the hole 102 is a flexible member 104 preferably a wire of spring 20 steel which will bend readily and conform itself to different shapes. The flexible member 104 is bent into the shape of a loop 106 at the portion thereof which extends out of the end of the hole 102 nearest the top of the roll, this loop extending forwardly in a position to surround and engage the lasting margin of the forepart of the shoe upper when the shoe is operatively positioned in the machine. In other words, the loop 106 curves around the roll 96 from the hole 102 and, when the roll is in an operative position, extends forwardly substantially in the plane of the forepart of the shoe bottom. The opposite direction of the flexible member 104, which extends out of the lower end of the hole 102, curves 25 rearwardly around the bottom of the roll and forms a loop 108 which lies substantially in the plane of the heel seat portion of the shoe bottom and is in a position to surround and engage the lasting margin of the heel seat portion of the upper, as shown in Figs. 2 and 3. The lateral adjustment of the roll 96 provided by the eccentric pin 84 referred to is sufficient to position the hole 102 and the flexible member 30 substantially midway of the shank portion of the shoe irrespective of its width. The rounded ends

of the hole in conjunction with the flexibility of the wire 104 will permit the intermediate portion of the wire to slip readily through the hole during rotation of the roll if one loop or the other should be held against movement longitudinally of the shoe bottom during such rotation. 5

When the roll is rotated the loops 106, 108 are caused to engage the lasting margins of the upper located at the toe and the heel seat portions of the shoe and to work these margins over the shoe bottom into overlasted position, this operation being preferably facilitated by the operator grasping the marginal portions of the upper above the wire loops to insure that both loops will be moved into operative engagement with the upper during the initial rotation of the roll and that thereafter the pressure or pull of the loops in working the lasting allowance of the upper over the margin of the insole is substantially uniform at both portions of the shoe bottom. 15

As shown in Fig. 1, the roll 96 and the flexible lasting member 104 are initially located in an upwardly inclined position at one side of the supporting members 28, 34, thereby providing ample space for the shoe to be mounted in these members without interference from the roll. The roll and lasting members are arranged to be swung downwardly into the position shown in Fig. 2, and the roll thereafter rotated to actuate the looped member in the following manner. 20

30 Mounted for reciprocating movement lengthwise of the lateral projection 88 on the casting 86 is a rack bar 110 having teeth 112 (Fig. 3) meshing with the teeth of the pinion gear 92. 35 The lower end of the rack bar 110 is pivotally connected by a pin 114 to the upper end of a rod 116 adjustably connected by a turnbuckle 118 to a lower rod 120 having a slot 122 at its lower portion. The cylinder 56 has a screw 124 mounted therein which passes through the slot 122 in the lower rod 120 so that, upon downward movement of the cylinder, the entire rod is lowered to operate the rack bar 110 and thereby to rotate the pinion 92 and roll 96. The amount 40 that the pinion and roll are rotated in a clockwise direction, as viewed in Fig. 3, is governed by the distance the cylinder 56 is lowered by depression of the treadle 74, this rotation, of course, operating the oppositely disposed loops of 45 the flexible member to work the upper into overlasted position. The amount that the pinion and roll 94 may be rotated in an opposite or counterclockwise direction is determined by a stop pin 126 projecting from the lower end of the 50 rack bar 110 and having a flattened upper side adapted to engage a groove or notch 128 formed in the lower end of the projection 88. When the mechanism is in this latter position, as shown in Fig. 1, the pin 124 on the cylinder is at the 55 upper end of the slot 122 and the roll 96 is in its initial or inoperative position with respect to its rotation. A relatively light tension spring 130 (Figs. 1 and 2) is secured at its upper end to a pin 132 in the casting 88 and at its lower end to 60 the lever 20 for the purpose of swinging the roll automatically into a substantially horizontal or operative position over the shoe so that it will be in a position to actuate the looped portions of the lasting member when the roll is rotated 65 by the rack bar. 70

In operating the machine to secure a shoe upper in overlasted relation to an insole, a shoe upper A, assembled with an insole B (Fig. 2) on a last C, is placed between the supporting mem- 75

bers 28, 34 when the latter are positioned, as shown in Fig. 1, the members 28, 34 always being sufficiently close to each other when in their inoperative position to support the shoe loosely between them. The marginal portion of the outer surface of the insole B and the inner surface of the shoe upper will have first been coated with a cement suitable for securing the upper in lasted relation to the insole. 10 Cements which may be used for this purpose are preferably those which are tacky when applied or which become tacky in a relatively short time thereafter such, for example, as latex or other types of rubber cement. The operator depresses the treadle 14 to lower the cylinder 56 and, through the spring-pressed piston arrangement 58, 62, to swing the upper arms of the levers 20, 22 toward each other to cause the shoe supporting members 28, 34 to grip the 15 opposite sides of the shoe yieldingly over areas extending substantially from the tip line to the heel breast line, as shown in Fig. 3. The shoe upper is thus clamped firmly against the last by the yieldable facings on these supporting 20 members and the lasting margins of the upper at the opposite sides of the shoe are worked over the outer face of the insole B and into lasted position, as shown in Fig. 2.

As the cylinder 56 descends and the levers 20, 22 swing toward each other to grip the shoe, the angle of the casting 68 and roll 96 on the lever 20 becomes such that the casting is more nearly balanced above its pivot 84 and the light spring 130 is then sufficient to pull it forwardly automatically into the substantially horizontal position shown in Fig. 2, this latter position being determined by the upper face of the lateral projection 30 on the lever 20. The roll 96 is then in a position transversely of the shank portion 35 of the shoe bottom to actuate the flexible lasting member 104 and to cause the loops 106, 108 to move into engagement with the margins of the shoe upper at the toe and heel seat portions of the shoe bottom and to work these margins over 40 the edges of the insole and into lasted relation thereto. The operator will now make sure that the looped portions 106, 108 of the flexible member are surrounding the lasting margins of the upper and he may preferably grasp the upper 45 above said looped portions to insure that the latter exert a wiping pull thereon and also to insure that, if one looped portion engages the upper before the other, the portion of the wire passing through the roll will slip until both 50 looped portions are in operative relation to the marginal portions of the upper.

As the treadle is depressed further the pin 124 on the cylinder engages the lower end of the slot 122 in the rod 120 and lowers this rod to reciprocate the rack bar 110 and rotate the pinion 92 and roll 96. Rotation of the roll draws the looped portions of the flexible lasting member toward each other lengthwise of the shoe until the lasting margins of the upper at both the toe end and the heel seat portion of the shoe are worked entirely over the marginal portion of the insole and have become secured in lasted relation thereto by the cement.

The operator may then release the treadle, which is returned to its elevated position by the compression spring 80, thereby elevating the cylinder 56 and returning the casting 86 and roll 96 to the position shown in Fig. 1, this action 70 putting a tension on the spring 130 which is

utilized thereafter in swinging the roll into its horizontal position for operating on another shoe, as explained above. The side lasting members or supports 28 and 30 are by this same action returned to their open positions ready to receive another shoe. 5

Having thus described my invention, what I claim as new and desire to secure by Letters Patent of the United States is:

1. In a machine for lasting shoes, the combination of means for supporting a shoe, a flexible member for working the lasting margin of the shoe upper into overlasted relation to an insole, and means for actuating said flexible member to cause it to operate on portions of the upper located at separated portions of the shoe bottom simultaneously and in planes substantially parallel to the planes of the shoe bottom at which said portions of the upper are located. 10

2. In a machine for lasting shoes, the combination of means for supporting a shoe, a flexible member for engaging the lasting allowance of the shoe upper and working it into overlasted position relatively to an insole, and means for actuating said flexible member to cause it to operate simultaneously on opposite end portions of the upper in planes substantially parallel to the planes of the opposite end portions of the shoe bottom. 20

3. In a machine for lasting shoes, the combination of means for supporting a shoe, a looped member for engaging the opposite end portions of the shoe upper and working them into overlasted relation to an insole, and means for supporting said looped member constructed and arranged to position the looped portions thereof in proper planes for operating simultaneously on said opposite end portions of the upper. 30

4. In a machine for lasting shoes, the combination of means for supporting a shoe, a flexible member provided with loops for engaging and working the forepart and heel portions of the shoe upper into overlasted position, and a roll for supporting and simultaneously actuating the loops of said member, said roll extending transversely of the shank portion of the shoe when in operative position and being of a diameter that positions said loops in planes substantially parallel to the planes of the forepart and the heel portions of the shoe bottom respectively. 40

5. In a machine for lasting shoes, the combination of means for supporting a shoe, a roll extending transversely of the shoe bottom when in an operative position and provided with a hole crossing its own axis, a flexible member passing through said hole and provided with loops for engaging and working the toe and heel portions of the shoe upper simultaneously into overlasted position, and means for rotating said roll. 50

6. In a machine for lasting shoes, the combination of means for supporting a shoe, a flexible member provided with oppositely disposed loops for working the portions of the shoe upper at opposite ends of the shoe into overlasted position, and rotatable means for actuating said flexible member constructed and arranged to permit said member to slip relatively to said rotatable means if one of said loops should be in a position to operate on the upper before the other loop is in such position, thereby insuring that both portions of the upper will be lasted simultaneously irrespective of their being initially located unequal distances from their respective loops. 60

7. In a machine for lasting shoes, the combina- 75

tion of means for supporting a shoe, a rotatable roll extending transversely of the shank portion of the shoe when in an operative position and provided with a diametrical hole at right angles thereto, a flexible wire passing loosely through said hole and having a loop at one end of the hole for working the toe portion of the shoe upper into overlasted position, and a loop at the other end of the hole for working the heel seat portion of the upper into overlasted position, the diameter of said roll being such that said loops operate in planes substantially parallel to the planes of the portions of the shoe bottom upon which the respective loops are arranged to operate, and the arrangement of the wire and roll being such that, if one loop engages the upper before the other loop, the wire slips lengthwise through the hole until said other loop is in upper engaging position, and treadle operated means for rotating said roll.

8. In a machine for lasting shoes, the combination of means for supporting a shoe, a flexible member for working the portions of the shoe upper at opposite ends of the shoe into overlasted position, a roll for supporting and actuating said member, said roll being arranged to swing from an inoperative position at one side of the shoe into a substantially horizontal operative position extending transversely of the shank portion of the shoe, and means for swinging said roll into said operative position and for thereafter rotating the roll to actuate the flexible member so that it operates on both end portions of the upper simultaneously and with substantially equal force.

9. In a machine for lasting shoes, the combination of means for supporting a shoe, a wire formed into loops for working the portions of the upper at the toe and heel portions of the shoe into overlasted position, a roll for supporting said wire and actuating said loops, said roll being arranged to operate in such a position transversely of the shoe bottom that it applies tension to the loops in planes substantially parallel to the planes of the shoe bottom over which the loops operate, and means for rotating the roll to actuate the loops simultaneously.

10. In a machine for lasting shoes, the combination of means for supporting a shoe at opposite sides thereof between its toe and heel portions and for working the upper at said opposite sides into overlasted position, flexible means provided with loops for working the toe and heel portions of the upper into overlasted position,

and single means for actuating said supporting means and said flexible means, thereby to work the entire upper into overlasted position.

11. In a machine for lasting shoes, the combination of members for supporting a shoe, said members engaging the opposite sides of the shoe between its toe and heel seat portions and being adapted to be moved yieldingly toward the shoe to work the opposite sides of the upper between said toe and heel seat portions into overlasted position, a flexible member provided with oppositely extending loops for working the toe and heel seat portions of the upper into overlasted position, a roll supporting said flexible member and rotatable to actuate said member, said roll being arranged to be swung into a position extending transversely of the shoe bottom from an upwardly inclined position at one side of the shoe, and single means for moving the shoe supporting members yieldingly toward the shoe to work the opposite side portions of the upper into overlasted position, for swinging the roll into said transverse position, and for thereafter rotating said roll to cause the loops of the flexible member to work the toe and heel seat portions of the upper simultaneously into overlasted position.

12. In a machine for lasting shoes, the combination of members for supporting the opposite sides of a shoe between its toe and heel seat portions, said members being also operable to work the lasting margins of the upper at the sides of the shoe engaged thereby into overlasted position, pivoted levers for supporting said members, a roll carried by one of said levers and arranged to swing from an upwardly inclined inoperative position to an operative position over the shoe, a flexible member carried by said roll and having loops arranged by rotation of the roll to work the toe and heel seat portions of the upper simultaneously into overlasted position, means for moving said levers yieldingly toward the shoe to cause the supporting members to operate on the opposite sides of the upper, resilient means for swinging said roll and flexible member into operative position over the shoe as the levers operate, and means actuated by the operation of said moving means and in timed relation thereto for rotating the roll to cause the loops on said flexible member to work the toe and heel seat portions of the upper simultaneously into overlasted position.
